(57) CLAIM

The ornamental design for a reversible crown, as shown and described.

DESCRIPTION

FIG. 1 is a perspective view of a reversible crown of this invention shown on a person's head;

FIG. 2 is an enlarged top plan view of the present invention;

FIG. 3 is an enlarged bottom plan view of the present invention;

FIG. 4 is an enlarged side elevational view of the present invention;

FIG. 5 is an enlarged front elevational view of the present invention;

FIG. 6 is an enlarged rear elevational view of the present invention; and,

FIG. 7 is a perspective view of the present invention in an inside out position showing a pattern that is different than that shown in FIG. 1.

The broken line showing a human form in FIG. 1 is for illustrative purposes only, and forms no part of the claimed design. The SF and 49ERS symbols shown in FIG. 1, which do not form part of the claimed design, are registered trademarks of the San Francisco Forty Niners, Ltd. The broken line shown in FIG. 7 is not part of the claimed design.
